UNITED STATES PATENT OFFICE

JOHN V. RICE, JR., OF BORDENTOWN, NEW JERSEY, ASSIGNOR TO RICHARD C. SCHWOERER, OF PHILADELPHIA, PENNSYLVANIA

CARBURETOR

Application filed July 12, 1927. Serial No. 205,097.

This invention relates to certain new and useful improvements in carburetors, having for a leading object among many that might be mentioned the provision of an automatically operative and adjustable fuel-mixing mechanism which will commingle and regulate the mixing of the air and gas or other fuel ingredients, in just the proper proportions at all times and under all atmospheric conditions, so as to enable the combustion of the fuel to be as complete as possible and to develop large power, thus subserving the interests of economy and efficiency.

And with these and other objects in view my invention consists essentially in the construction, combination, and arrangement of parts, substantially as will be hereinafter described and claimed.

In the accompanying drawing illustrating my invention:

Figure 1 is a vertical section of my improved carburetor on the line 1, 1, of Figure 2.

Figure 2 is a horizontal sectional plan view on the line 2, 2, of Figure 1.

Figure 3 is a horizontal plan view on the line 3, 3, of Figure 1.

Figure 4 is a horizontal section on the line 4, 4, of Figure 1.

Figure 5 is a horizontal sectional plan view on the line 5, 5, of Figure 1.

Figure 6 is a detail bottom plan view of the conical valve-opening member of the oil or gas control inlet mechanism.

Like characters of reference designate like parts throughout all the different figures of the drawing.

The casing of the carburetor, in the example of its construction herein offered for explanatory purposes, consists of several sections united together by bolts or secured in proper relation to each other by any other suitable means; as for instance, the top section 1, the next section 2 of virtually the same diameter with an interposed thin plate 38 between the sections 1 and 2; the smaller section 3 below section 2; and the still smaller lower section 4; all the sections being hollow and properly related and combined to perform their proper functions and so shaped and sized as to accommodate the operative

mechanical parts, and allow the flow of gas and air.

The top section 1 is supported in any desired manner on some part of an engine, or elsewhere, as for example by the use of screws entering the screw holes 53 in top plate 54. Section 1 has also an exhaust inlet 24 through which the hot exhaust gas or combustion products from the engine enter the carburetor to heat the same. Also secured to the side of section 1 by screwing the hollow boss 34 into the wall of section 1 is the thermostat casing 26; and the wall of section 1 has a hollow cavity 35 therein whose outside wall is perforated at 36 to admit outside atmospheric air for use in starting the operation of the device, said cavity 35 being in communication with the cavity 37, so that the preliminary air will pass through the latter, and on as I will describe.

Supported centrally in the interior of the section 1 is a Venturi tube A, which is an important feature. It has the frustro-conical upper part 22 which is attached to the upper wall 54 and delivers fuel through the same to the fuel intake of the engine; and it has also the broad curved bottom portion 23 whose circular periphery is rigidly held close to the outside wall of the section 1, or preferable between the bottom edge of section 1 and the interposed plate 38. The venturi is surrounded by the hot exhaust.

The boss or nozzle 34 which screws into the side wall of the section 1 and forms a part of the thermostat casing 26 having inner chamber B, has a passage 25 through it, through which passes the hot exhaust from casing section 1. The casing 26 also has an outlet nozzle 30, to which a pipe may be coupled for carrying away this exhaust. Also in the casing 26 is a plate 27 holding a diaphragm 29 which is acted on by the heat to expand and contract; and it carries a pin 55 having one end guided by a bearing 56 while the other end carries a valve disc or cover 28, which is in front of the passage 25 and which moves towards and away from the end of the passage, so that it opens and closes the same from time to time, accordingly as the flexure of the diaphragm 27 is controlled by the heat. Thus when the heat of the inside

chamber and the venturi A is at a certain degree the stopper 28 will open or will close and when open the hot gases will escape at outlet 30.

5 The air passage 37 in wall of section 1 connects through vertical passage 39 (which leads through wall of section 1 below passage 37, the peripheral edge of venturi A, the interposed plate 38 and a part of wall of section 2) into cavity 40 in the wall of section 2, and thence through passage 43 into chamber 57 in one end of casing of section 3, there being in the remainder of section 3 another chamber 52, which serves as a mixing chamber for the preliminary air and gas to produce the gaseous fuel. When there is no air in same, chamber 52 holds gas, oil, or vapor. Access from chamber 57 to chamber 52 is had through a circular opening 49, under the control of a curved valve plate 51, wherein is a circular opening 50, which coincides with opening 49 more or less when the valve is open more or less, and sometimes plate 51 closes the opening 49, so as to cut off the passage of air completely. This valve plate 51 is formed as a vertical part of a rotatable convex-shaped member 13, shown in cross-section in Figure 1 and in reverse plan in Figure 6. It is obvious that air entering through the perforations 36 flows through the connected spaces as described until it enters the mixing chamber 52 where it mixes with the vaporized gasoline in the space 18 under member 13. This is the preliminary amount of air which is used in starting.

40 The main air inlets are at the sides of the casing section 2, at the openings 47 and 48 for example, see Figure 4. They are controlled, as to the extent of opening and closing, by the shutter or leaf valve consisting of vertical plates 45 having an integral central hollow tube 21 revolvable in a central bearing in plate 38, said shutter plates 45, 45, projecting in line with each other in opposite directions from tube 21, and movable back and forth with relation to a pair of stationary plates 44 and 44, that are secured to the outer wall of the casing section 2 and have their inner ends contiguous to the tube 21. The movable and stationary plates therefore have the V-shaped openings between them, as seen in Figures 3 and 4, said entrances 47 and 48 being shown as closed 45 when the plates occupy this position. For, above the valve plates 44 and 45 is the horizontal diaphragm or plate 38 which is held between sections 1 and 2; and below plates 44 and 45 is the solid floor of section 2. The 50 plate 38, see Figure 2, is formed with openings 41 and 42, between which are the solid parts 41^a and 42^a. When the leaves 44 and 45 are in the closed position shown in Figure 2, or in Figure 3, air cannot pass from the V-shaped air entrances 47 and 48,

since said entrances are covered by the solid parts 41^a and 42^a, see Figure 2; but when the movable plates 45 turn on their swiveled center tube 21 away from the stationary leaves 44, an opening of greater or less size is made into openings 41 and 42 so that air can pass from the entrances 47 and 48 through openings 41 and 42 into the Venturi tube A and be commingled with the gas arriving in the member A from end 31 of central tube 21. The more the leaves 45 turn on their pivoted support the larger will be the air passage through openings 41 and 42. As these leaves 45 thus open they pass into the position shown in dotted lines in Figure 3, and stretch the spring 46 attached to one of leaves 45 and one of leaves 44. This spring 46 acts to return the valve leaves 45 to closed position when the suction or vacuum that opens the leaves 45 ceases to act, or varies in its action.

70 The opening of leaves 45 is limited by the pin 32 held in a socket 33 on section 2, against the end of which pin one of the plates 45 strikes. The pin 32 can be adjusted in its 75 socket so as to regulate the extreme limit of the opening of the air-admission valves; and for convenience in regulating and positioning the pin 32, its outer end, or some attachment thereto, may extend to any desired point on the engine or elsewhere, so as to easily control the character of the mixture, as to richness and facility of combustion. Obviously the 80 vacuum action of the engine and the suction effect on the carburetor swings the air-admission valves open, and causes the plates 45 to vibrate, thus automatically regulating the 85 consumption of air, and producing and supplying the fuel mixture to the cylinders as required.

90 The tube 21, swiveled to turn in plate 38 so as to act as a hinge for the valve leaves 45, and having the function of carrying the fuel mixture into the Venturi tube A at starting and the gasoline vapor or gas after the starting air 95 stops, has an integral step plate 58 in the bottom of section 2 which rotates gradually back and forth. The lower end of tube 21 below plate 58 screws into the boss 59 projecting upwardly from the convex member 13, located in section 3, below which member 13, on the concave side thereof, is the space 18, which communicates with the rotary tube 21 through a passage 20 in boss 59. The rotation of tube 21 and the attached convex member 13 is facilitated by the ball bearing 19 carried in the bottom of section 2. The convex member 13 is provided on its lower side with ribs 16 and 17, 16 being short and 17 longer, but both in the same circle, which 100 control the opening and closing of the ball gas valves 14 and 15 arranged in block or casting 60, mounted on screw plug 11, as I 105 will presently more fully specify.

110 Below the section 3 of the carburetor casing 115

is the bottom end section 4, which need not be very large in size, and whose top plate has an integral upwardly-projecting bearing 10, internally screw-threaded and receiving the screw plug 11 which is screwed through the same with its lower end in the chamber 7, in section 4 and its upper end in the chamber 52 in section 3, said upper end being enlarged or T-shaped in cross-section and screwed into the lower side of valve-carrying block 60 having oil chamber 61 therein. The screw 11 has a central passage 12, with a countersunk lower end 62 and its upper end delivering into the space 61 below valved block 60, which space 61 connects with recesses or cavities in said block 60 which have outlets or seats 63, see Figure 5, for the ball valves 14 and 15 employed as gas or oil outlet valves and supplied with closing springs which normally close the balls against the seats and prevent the passage of any gas or liquid except when the ribs or cams 14 and 15 on the convex plate 13 press against one or both of said valves 14 and 15 from without and open the valves for the passage of vapor. Further, chamber 7 receives gasoline through the strainer end 8 of supply pipe 9, and needle valve 5 passing through bearing 6 engages the countersunk end 62 of passage 12, opening said passage to a greater or less extent so as to allow more or less gasoline to pass for vaporization and use in the fuel mixture.

As the tube 21, serving as a valve leaf pivot, rotates, it turns the convex member 13, which carries air-valve plate 51, and gas-valve operating ribs 16 and 17. If the valve plate 51 is open and one of the oil valves 14 and 15 is open, the air and vapor will unite to form the mixture which passes into the Venturi tube 22 from end 31 of tube 21 and enters the cylinders of the engine. If the starting air is entirely cut off by the closing of ports 49 and 50 by movement of plate 51, the oil passing out of one or both of the valves 14 and 15 will pass into space 18 and thence through pipe 21 and out of the end 31 thereof where it will mix with the air supplied through openings 41 and 42 to the lower Venturi chamber 23 and thence to the upper Venturi chamber 22. The ribs 16 and 17 on member 13 are of unequal length, as stated.

The operation of my improved carburetor will be clearly evident from the foregoing description of the construction, combination and arrangement of parts. The heat of the exhaust from the engine passing through the upper chamber warms the chamber and imparts heat to the air entering at 36, which flows down through the passages in the wall and mingles with the gasoline vapor in chamber 52 and space 18, passing thence through valves 14 and 15, one or both, and the mixture ascends through tube 21 to the venturi A and then to the engine. The thermostat in chamber B regulates the amount of heat which is

derived and utilized from the flow of the exhaust. The air supplied at first by valve 49 and 50 is the starting air, for after the device begins to feed a substantial amount of fuel to the engine, the air supplied by valve 49 and 50 will be reduced or graduated, varying in amount from time to time as required to meet the demand thereon for the mixture and the suction effect of the engine on the Venturi tube A will gradually open the valve leaves 45 and will cause a greater or less volume of air to enter from the outside atmosphere through openings 47 and 48, and openings 41 and 42, and flow into the venturi and mix thoroughly with the vaporized gasoline delivered at 31 through tube 21.

The tube 21, which is attached to the valve members 45, rotates more or less in proportion to the action of the suction on said members 45, and this revolves the conical member 13 which controls the inlet valves 14 and 15 that admit gas or oil to be vaporized and mingled with the air. At one time only one of said valves will be open, as for example, valve 15, as it is acted on by the long rib 17, see Figures 5 and 6. This rib may move some little distance on valve 15, depressing same and keeping this one valve only open, thus supplying only a certain amount of vapor, but as a richer mixture is needed, or more fuel is needed for use, the continued rotation of member 13 will cause valve opening projection 16 to encounter and depress valve 14, so that both valves 14 and 15 will be simultaneously open and hence a much larger supply of gasoline vapor will be introduced into the mixture with a correspondingly large amount of air. The operation will be entirely automatic and may be regulated and controlled so as to create just the proper degree of richness in the mixture for the duty it is to perform. The supplies of air and gas are graduated to a nicety with the combination mixture which is effective, economical and constant.

Having thus described my invention, what I claim as new and desire to secure by Letters Patent, is:

1. In a carburetor, the combination with a casing, having an inlet for the hot exhaust from an engine, and having also preliminary air and oil inlets, of a Venturi tube supported in the casing and heated by the exhaust, a central vapor tube that delivers into the venturi and carries a valve-operating member having ribs thereon, air valve plates actuated by suction and moving said tube as a pivot, and a series of valves for the oil that are opened in succession by the ribs for automatically proportioning the inflow of oil to the intake of air.

2. In a carburetor, the combination with a casing and a heat-exposed Venturi tube supported therein, of a central rotating tube delivering into the venturi, said tube carrying a convex member having a plurality of

integral valve-opening ribs, air-valve plates carried by said rotating tube and movable to open for the air to pass to the venturi, and one or more valves controlled by the aforesaid ribs to admit oil to the central tube by which it flows into the venturi to mix with the air, and means for supply oil, in which means said valves are located.

3. In a carburetor, the combination with a casing and a Venturi tube supported therein, of a central rotating tube delivering into the venturi and provided with movable air-valve plates, stationary air-valve plates in the casing having a V-relation to the movable tube-carrying plates to provide inlets for the air, means in the casing providing passages into the venturi controlled by the automatic opening and closing of the moving plates to admit air into the venturi, a rotary member carried by the tube and having a valve-actuating lug, an oil inlet valve operated by said lug as the rotary member revolves, and means for supplying oil consisting of an inner casting having a central oil chamber and an oil passage leading thereto and carrying the aforesaid oil inlet valve.

4. In a carburetor, the combination with a casing and a Venturi tube supported therein, of a central rotating tube delivering into the venturi and provided with movable air-valve plates, stationary air-valve plates in the casing having a V-relation to the movable plates carried by the tube to provide inlets for the air, means in the casing providing passages into the venturi controlled by the automatic opening and closing of the said moving plates to admit air into the venturi, a rotary member carried by the tube, a chamber containing said rotary member, and valve mechanism in said chamber actuated by the rotary member to admit oil or vapor to the central tube to be carried to the venturi.

5. In a carburetor, the combination with a casing and a Venturi tube therein, of a central rotating tube delivering into the venturi and provided with movable air valve plates, stationary air-valve plates in the casing having a V-relation to the movable plates carried by the tube to provide inlets for the air, means in the casing providing passages into the venturi controlled by said movable plates, and means consisting of an adjustable pin for regulating the limit of movement of the movable plates, an oil chamber, and valve mechanism controlling the supply of oil therefrom to the central tube leading to the venturi, where the fuel mixture is formed.

6. In a carburetor, the combination with a casing and a Venturi tube, supported therein, of a central rotary tube delivering into the venturi and provided with air-valve plates movable on the tube as a pivot, stationary air valve plates in the casing having a V-relation to the movable plates carried by the tube to provide inlets for the air, means in

the casing providing passages into the venturi controlled by the automatic opening and closing of the moving plates to admit air into the venturi, a rotary member carried by the tube and having valve-actuating ribs, oil inlet valves for admitting oil to pass into said tube operated by said ribs as the rotary member revolves and consisting of yielding balls, and an interior oil chamber in the walls of which the said ball valves are mounted, together with means for supplying oil to said chamber.

7. In a carburetor, the combination with a casing and a Venturi tube supported therein, of a central rotary tube delivering into the venturi and provided with air-valve plates movable on the tube as a pivot, stationary air valve plates in the casing having a V-relation to the movable plates carried by the tube to provide inlets for the air, means in the casing providing passages into the venturi controlled by the automatic opening and closing of the moving plates to admit air into the venturi, a rotary member carried by the tube and having a pair of valve-actuating ribs, one longer and one shorter and both curved in arcs of the same circle, and oil inlet valves for admitting oil to pass into the central tube, operated by said ribs as the rotary member revolves, sometimes one and sometimes both, and consisting of yielding balls, and a casing member for the balls.

8. In a carburetor, the combination with a casing and a Venturi tube supported therein, of a central rotary tube delivering into the venturi, air-inlet valve mechanism connected to said tube, a rotary member carried at the lower extremity of said tube and having on its under side a pair of valve-actuating ribs curved in the arcs of the same circle, and oil inlet valves for admitting oil to the tube to be carrier to the venturi consisting of yielding balls operated by said ribs to open as the rotary member revolves.

9. In a carburetor, the combination with a casing and a Venturi tube supported therein, of a central rotary tube delivering into the venturi and provided with air-valve plates movable with the tube as a pivot, stationary air-valve plates in the casing and having a V-relation to the movable plates carried by the tube to provide air inlets, means in the casing providing passages into the venturi controlled by the movable valve plates, a rotary member carried by the tube and having valve-actuating ribs, and having also a perforated air-valve flange, yielding inlet valves for oil adapted to be opened by the valve-actuating ribs, an air chamber for supplying starting air, said chamber having a perforated wall cooperating with the perforated air valve flange, all arranged to supply first a starting mixture and afterwards the regular running mixture.

10. In a carburetor, the combination with

a casing having an exhaust inlet, an exhaust outlet, and an inlet for the preliminary air, a heat exposed venturi in said casing having a conical top part and a flaring lower portion, 5 inlet means for air into said lower portion, a valve for the exhaust outlet, a thermostat for regulating the action of said valve, a rotary central tube provided with valve devices for admitting air to the air-inlet means for the lower portion of the venturi, a valve for controlling the admission of the starting air, an oil chamber, valve mechanism controlling the passage of the oil into the rotary tube, and means actuated by the rotary tube for 10 operating said latter valve mechanism in proper relation to the operating devices which admit the starting air and the main air supply.

In testimony whereof I hereunto affix my 15 signature.
